UNITED STATES PATENT OFFICE

2,124,433

MOTOR-COMPRESSOR ARRANGEMENT

Friedrich Schmidt, Berlin-Karlshorst, Germany,
assignor to General Electric Company, a corporation of New York

Application February 24, 1938, Serial No. 192,349
In Germany March 3, 1937

1 Claim. (Cl. 60—6)

The present invention relates to compressor arrangements comprising a compressor or blower driven by a motor or prime mover and arranged to supply compressed medium, such as air, to a consumer. More specifically the invention relates to the kind of arrangements in which such compressor furnishes air to a nitrogen fixation plant or like industrial apparatus consuming air and producing combustion gases as a by-product. The object of my invention is to provide an improved arrangement of the type above specified whereby better economy and high efficiency at variable demand for air by the consumer are attained. This is accomplished in accordance with my invention by an arrangement which includes a gas turbine as an auxiliary or supplemental drive for the compressor which turbine is connected to receive the combustion gases produced as a by-product in the industrial apparatus and also a portion of the compressed air or medium discharged by the compressor during low load condition.

For a better understanding of what I believe to be novel and my invention, attention is directed to the following description and the claim appended thereto in connection with the accompanying drawing.

The single figure of the drawing illustrates diagrammatically a compressor arrangement embodying my invention.

The arrangement comprises a centrifugal compressor 10 which has an inlet conduit 11 and a discharge scroll 12 and is driven through a gearing 13 by a prime mover, in the present instance an electric motor 14. The discharge scroll 12 is connected by a conduit 15 to a consumer 16, such as a nitrogen fixation apparatus requiring compressed air during operation and producing combustion gases as a by-product. These combustion gases are conducted through a conduit 17 to the inlet of a gas turbine 18 arranged to drive the compressor 10. The turbine 18 thus utilizes combustion gases produced by the apparatus 16 for driving the compressor 10, thereby reducing the amount of power required by the

The efficiency of the centrifugal blower 12 drops considerably with decreasing demand for compressed air by the apparatus 16. In order to operate the centrifugal blower at full or normal load during varying demand for compressed air by the apparatus 16, I provide in accordance with my invention means for conducting some of the air discharged from the compressor 12 to the gas turbine 18. This means in the present instance comprises two conduits, a conduit 19 with a valve 20 connected between the conduits 15 and 17 and another conduit 21 with a valve 22 connected between the conduits 15 and an intermediate stage of the gas turbine 18. During normal load conditions the valves 20 and 22 are closed. Upon decreasing demand for compressed air or like medium one of the valves 20 and 22 is opened to conduct some of the compressed air from the conduit 15 to the inlet or an intermediate stage respectively of the turbine 18. With this arrangement the centrifugal compressor 10 may be operated at all times with full load output and accordingly at maximum efficiency. If the demand for compressed air is high, all of the air is conducted to the apparatus 16 and if the demand for compressed air is low, some of it is used to drive the turbine 18.

What I claim as new and desire to secure by Letters Patent of the United States is:

A compressor arrangement comprising a centrifugal compressor, a motor for driving the compressor, an apparatus requiring compressed medium during operation and producing combustion gases as a by-product, a conduit for conducting compressed medium from the compressor to the apparatus, a gas turbine having an inlet connected to the apparatus to receive combustion gases therefrom for driving the compressor, and conduit means for conducting during low load condition of the compressor some of the compressed medium to the gas turbine to permit operation of the compressor at maximum efficiency during varying load demand from the apparatus.
